UNITED STATES PATENT OFFICE.

ELWOOD WICKS FORNEY, OF GALENA, KANSAS.

PIN-HOLDER.

No. 892,820.

Specification of Letters Patent.

Patented July 7, 1908.

Application filed December 9, 1907. Serial No. 405,734.

To all whom it may concern:

Be it known that I, ELWOOD WICKS FORNEY, a citizen of the United States, and a resident of Galena, in the county of Cherokee 5 and State of Kansas, have made certain new and useful Improvements in Pin-Holders, of which the following is a specification.

My invention is an improvement in devices or apparatus adapted for holding pins and 10 projecting them singly into position for manual seizure and withdrawal when wanted for use.

In carrying out my invention, a paper strip or roll, in which pins are inserted and held in 15 the usual way, is coiled within a holder that is hinged, and supported by a spring in such manner that it may be depressed manually, which movement operates mechanism that advances the pin strip step by step and simultaneously projects a single pin from the 20 top of the holder, where it may be conveniently seized and removed.

The details of construction and arrangement and operation of the apparatus are as 25 hereinafter described, the novel features being indicated in the claims.

In the accompanying drawings illustrating the invention—Figure 1 is a perspective view of my improved pin holder. Fig. 2 is a 30 longitudinal vertical section on line 2—2 of Fig. 3. Fig. 3 is a horizontal section on line 3—3 Fig. 2. Fig. 4 is a horizontal section in a plane below the one indicated in Fig. 3—see line 4—4 of Fig. 8. Fig. 5 is a detail 35 horizontal section illustrating particularly the means for rotating the drum by which the pin-strip is advanced step by step. Fig. 6 is a longitudinal section of the pin holder on line 6—6 of Fig. 3 showing the hinged part 40 depressed as required to force a pin upward out of the pin strip. Fig. 7 is a vertical cross section of the pin holder on a plane (7—7, Fig. 2) adjacent to the front end of the same. Fig. 8 is another vertical section on line 8—8 45 of Fig. 2 in a plane in rear of that shown in Fig. 7. Fig. 9 is a perspective view of the means for rotating the drum by which the pin strip is advanced, the said means being shown enlarged. Fig. 10 is a perspective 50 view of the parts disassociated, which comprises a frame or box-like holder proper for actuating mechanism, within which most of the operative parts are contained.

A indicates a box-like part which is open at 55 the top and partly so at the front end, and B

is a part hinged within the receptacle A and adapted to swing vertically therein, said part being in the nature of a box-like frame and adapted to contain most of the operative parts by which the pin-carrying strip is advanced and the pins ejected singly therefrom.

As shown in the perspective view, Fig. 10, the part B comprises a flat top 1, having a cone-shaped projection 2, which is provided with a cone-shaped perforation, see Fig. 6, through which the pins *x* are guided and ejected singly, as will be presently described. The body portion of the holder B comprises the flat bottom 3, having a front end 4, a rear end 5, and a side portion 6, all of which are preferably formed integral, or from a single sheet of plate metal. The upper ends of the front and rear parts 4, 5, are turned outward, thus forming flanges 7, which are perforated to receive rivets by which the top 1 is attached. It will be seen that the top 1 and bottom 3 are parallel and that the side 6 extends only about two-thirds of the way from rear 5 to front 4, while the side opposite 80 the part 6 is entirely open, as required for convenience in inserting a pin-strip, or pin-carrier, *y*; see Figs. 2 and 3. The cover 1 of holder B, is further provided at its rear end with pendent lugs or ears 8, through which passes a rod 9, see Fig. 6, by which the holder is pivoted to the upper rear corner of the receptacle A. The depth of the box-like holder B is so much less than that of the receptacle A so that the front end of the former may be depressed as shown in Fig. 6, and as required for ejecting a pin *x* through the guide 2, as will be further described. As shown in Fig. 3, the pin strip *y* is coiled in the chamber or rear portion of the holder 95 B and its outer end is attached to a slotted drum 10. The latter is attached to a shaft 11 that is journaled in the free end of a horizontal arm 12, see Fig. 9, the latter being in turn journaled on a post 13 that is fixed at 100 its ends in the top 1 and bottom 3 of the holder B, as shown in Fig. 8. A wire spring 14 is coiled about the post 13 and serves to press the arm 12 toward the end 4 of holder B, so that the pin-carrying strip in being wound on the drum 10, is held in contact with said part 4, as shown in Figs. 3 and 6. Another spring 15, see Fig. 9, is coiled about the lower end of the drum-winding shaft 11 and a horizontal arm 16, carrying a hinged 110

pawl 17, is mounted loose on the shaft below the spring and between it and a ratchet 18, which is fixed on the shaft. The pawl 17 is held normally engaged with the ratchet by means of a small spring 19 that is coiled about its pivot. The pawl is provided with a projecting end portion 17^a, which serves as a thumb catch for disengaging the pawl from the ratchet, as required when an empty pin-strip is to be withdrawn from the drum 10, an operation which is hereinafter explained. The spring 15 holds the pawl arm 16 normally retracted or pressed backward against a lug 20, which, as shown in Fig. 10, is preferably formed integral with the bottom 3 of the holder B, by slitting the said bottom and turning upward the tongue thus formed. A larger opening 21 is formed adjacently in the bottom 3 and a push-rod 22, which is pivoted to the pawl arm 16, curves downward through this opening 21 and extends backward practically parallel to the bottom 3 and beyond the rear end of the holder B, so that when the latter is depressed as shown in Fig. 6, the rear end of the push-rod 22 will strike the rear wall of the receptacle A, and thus push the free end of the pawl 16 forward, or away from the stop 20, as shown in Fig. 5, so that the pawl 17 may engage another tooth of the ratchet 18, or, in other words, take a new hold on the latter. When the part B rises from the position shown in Fig. 6 to the horizontal as in Fig. 1, 2, the spring 15 will carry the pawl arm 16 back into engagement with the lug 20, as shown in Figs. 4 and 9, whereby the winding-drum shaft 11 is rotated far enough to carry the pin-strip y the distance that intervenes between the pins x therein, thus bringing another pin under, and in alignment with, the conical guide 2 in the cover 1. It will be noted that, when the pawl arm 16 is thus swung on the winding post 11, the friction between the pin-strip on the drum 10 and the adjacent portion 4 of holder B, serves to prevent backward rotation of the drum. As shown in Fig. 10, the front end 4 of the holder B is provided with a vertical slot 23 and tongue 24 projecting inward at the top of the same, it being formed by slitting a portion of the front 4 as will be readily understood. This part 24 serves as a horizontal support and guide for the pin-strip y in passing on to the drum; see Figs. 2 and 6.

When the holder B is depressed as shown in Fig. 6, it is necessary that the pin x which is then in alignment with the conical guide 2, shall strike upon a fixed part in order to eject it from the pin-strip, as shown. For this purpose I provide what may be termed an abutment, or post, 25, the same being adapted to slide vertically in the slot 23, before described, the head of the same being notched, as shown in Fig. 4, to hold it in due position as it slides up and down. This post

is pivoted at its lower end, see Figs. 2 and 7, to the upturned front end 26 of a metal plate 27, whose broader rear end is provided with upturned ears 27^a, by which it is pivoted, see Figs. 2, 7 and 8, by rod 28 to ears 3^a 70 pendent from, and formed integrally with, the bottom 3 of the holder B. As shown in Figs. 2 and 6, the push-rod 22 passes over and is adapted to slide on its pivot rod 28, and between parallel guides 27^b, see Fig. 10, 75 the same being formed as an integral portion of the hinged plate 27. A spiral spring 29, see Figs. 2, 6, 8, is interposed between the plate 27 and the bottom 3 of the holder B at a point near the pivot 28, which spring tends 80 to press the free end of plate 27 downward; or, in other words, to hold it in contact with the base of the box-like receptacle A, as shown in Figs. 2, 6, 7. By this means the post 25 is always held down when the holder 85 B rises to its normal horizontal position after depression as shown in Fig. 6. The holder B is held raised to the normal horizontal position by means of a plate spring 30, which, as shown in Figs. 3 and 6, is attached to the 90 upper portion of the rear wall 5, of holder B, and its free end presses backward against the rear wall of the receptacle A. Since, however, the spring tends to raise the holder B above the horizontal, an automatic spring 95 catch 31 is provided, which as shown in Fig. 1, consists of an elongated metal plate riveted at one end to a side of part A, its free end being provided with a tongue 32, which, as shown in Fig. 8, projects through a slot in 100 the wall of part A and engages the bottom 3 of the holder B, thus preventing the latter rising too far by reason of the action of spring 30. The free end of the plate spring 31 projects beyond the end 5 of part A and thus serves as a thumb-piece by which the catch may be easily disengaged from the holder B when it is required to raise the same 105 out of the receptacle A.

In order to charge the apparatus with 110 pins, the spring catch 31 is pressed outward, thus releasing the holder B, which is swung upward and outward and the whole apparatus is laid on that side to which the catch is attached. As will be apparent, this leaves 115 the opposite side of holder B open or exposed, so that a coiled pin-strip, or pin-carrier, y, may be placed therein as shown; see Fig. 3. Then, by pressing on the free end of the push-rod 22, the pawl arm 16 is worked 120 until, through engagement of the pawl 17 with ratchet 18, the drum 10 is turned around so that the slot therein is exposed to view. Then the end of the pin-strip is inserted in the slot and the drum is rotated as 125 before to wind on a portion of the strip, or until the end of the strip passes between the drum and the front end 4 of the holder B, when the friction caused by the spring 14 on post 13 will hold the pin-strip from slipping. 130

The guide 24, see Fig. 10, aids at this time in supporting the strip in the required position. It will be seen that while the strip proper is on the winding-drum, the pins x project for 5 nearly half their length below it.

Instead of first placing the pin-strip roll or coil in holder B, and then attaching its end to the drum, the end of the strip may be first attached to the drum and then the coil 10 placed in proper position in the chamber of holder B by simply letting it fall thereinto, by which it will rest on the side 6 of the holder. Next, close the holder B into the part A until the spring catch 31 engages it, 15 when the apparatus is ready for operation. Then, by simply pressing with the thumb and finger resting on the opposite sides of the conical guide 2 downward on the front end of the holder cover 1, the same is carried 20 down to the position indicated in Fig. 6, or until the top of the post 25 strikes the head of the slot 23, see Figs. 6 and 10, and, since at this time a pin x will be directly over the post, said pin will be pushed upward so that 25 its head will project a considerable distance above the conical guide 2, as shown in Fig. 6, and well between the thumb and finger. Upon withdrawing the pin x with the thumb and finger, and releasing the pressure on the 30 holder B, the spring 30 raises it to the horizontal position where it is arrested by the spring catch 31. The pin x having been withdrawn and the holder B again depressed, the operation is repeated, and so on until all 35 the pins in the strip have been projected and withdrawn. When all the pins have been thus extracted, the pawl 17 will be held out of engagement with the ratchet 18, which will allow the winding drum 10 to rotate 40 backward so that the empty strip may be conveniently pulled from the drum.

The outside box-like receptacle or casing A, being made entirely separate from the other parts, it may be made of different material and designed in any manner that judgment or fancy may dictate, without affecting the operation of the working parts. Further, since the pivot pin 9 may be readily withdrawn, the holder B with all its contained parts and attachments may be readily removed, if it be required for convenience of access to the working parts or for other purposes.

I claim—

55. 1. A pin-holder adapted for holding and projecting pins singly into a position which adapts them to be conveniently seized, the same comprising a base part, a holder for operating mechanism hinged thereto at one end, a spring for supporting the same in normal position, an abutment upon which the pins may be caused to strike, and means for advancing or feeding a pin-holding strip and guiding it over the aforesaid abutment so 60 that upon depressing the free end of the

holder the pin is forced up out of the strip proper and thus made easily accessible, substantially as described.

2. The improved pin-holder comprising a base part, a spring supported holder hinged 70 to one end of the same, a stop for arresting the upward swing of the holder and means attached to the latter for winding on a pin-holding strip and for intermittently advancing the same when the holder is depressed, 75 and an abutment whereon the pins strike successively when the holder is depressed, thus causing protrusion of the pins from the holder, as described.

3. The combination with the base part, of 80 a spring supported box-like holder hinged thereto and adapted to swing vertically, means attached to and supported upon the holder for guiding a pin-holding strip and means for intermittently advancing or feed- 85 ing the same, the said means including a winding drum and shaft, a lever and ratchet and pawl mechanism operatively connected with the winding shaft, and a push-rod connected with the lever, which, when the holder 90 is depressed, automatically operates the feed mechanism, substantially as described.

4. The combination with the hollow base portion and a box-like holder hinged thereto at one end, a spring interposed between them 95 and normally supporting the holder in an elevated position, a releasable catch which prevents the holder from rising above a predetermined height, an abutment adapted to rest on the base and projecting into, and 100 adapted to slide in, the front portion of the holder, means arranged within the latter for advancing or feeding the pin-holding strip when the holder is depressed, the strip being guided over the aforesaid abutment so that 105 the pins therein are successively brought over the abutment and into contact with the same at each depression whereby they are projected upward successively into position for seizure and withdrawal, substantially as described. 110

5. In a pin-holder of the class described, the combination with a suitable base, of a member hinged thereto and carrying a pin-strip guide and a winding drum, of means for intermittently rotating such drum, the same 115 comprising a spring-pressed lever, a spring pawl and a ratchet which it normally engages, and a device connected with the lever which, when the said member is depressed with its contained parts, actuates the lever 120 and thereby the winding drum through the means of the ratchet-and-pawl mechanism, substantially as described.

6. An apparatus of the class specified comprising a base, a member hinged thereto, 125 means for supporting and winding a pin-strip or carrier, including ratchet mechanism, said member being depressible as required for ejecting the pins from the strip, and a pin abutment which is slidable vertically rela- 130

tive to the depressible end of said member, substantially as described.

7. In an apparatus of the class specified for delivering pins and like articles one at a time, the combination of a base or support, a holder hinged thereto, a spring supporting such holder, a rotary drum and ratchet-and-pawl mechanism arranged within the holder for winding a pin strip on the drum, a push rod for operating the aforesaid mechanism, said push rod being adapted for contact with the rear end of the base and an abutment upon which the pins strike and are thus forced upward when the holder is depressed, as shown and described.

8. The combination, with a base support and a holder hinged thereto, of a winding drum, a swinging pivoted arm in which the same is journaled, a spring tending to hold said drum pressed against a fixed portion of the holder, and means for actuating said drum for advancing the pin-strip when the holder is depressed, substantially as described.

25 9. The combination, with the base support, of a box-like holder hinged thereto, a winding drum, a lever arm journaled on a pivot fixed in the holder, the shaft of the winding drum being journaled in the free end of the arm, a spring coiled about the pivot of said arm, a ratchet fixed on the drum shaft, a lever arm which is rotatable on such shaft, a spring which tends to hold said arm in a certain normal position, a stop by which the arm is arrested, a spring pawl for engaging the ratchet, and a device connected with the lever and adapted, when the holder is depressed, to engage the base support and thus rotate the drum intermittently through the 40 ratchet-and-pawl mechanism, substantially as described.

10. The combination, with a base support, of a box-like holder hinged thereto and adapted to swing vertically, a spring for holding said holder normally elevated, means contained within the holder for winding on and advancing a pin-strip intermittently, and an abutment for the pins upon which they strike when the holder is depressed, a plate 45 pivoted beneath the holder and pivotally connected with the abutment, the latter being guided in the front portion of the holder,

and a spring interposed between the said plate and the holder proper whereby the plate and the attached abutment are held 55 constantly depressed, substantially as described.

11. The combination, with a suitable base and a frame hinged thereto, a spring for holding the frame normally elevated, means for arresting the frame at a certain height, mechanism attached to the frame for winding and intermittently advancing a pin-strip as the frame is depressed, and a sliding pin-abutment arranged in the front portion of the 65 frame and adapted to slide therein when the frame is depressed, substantially as described.

12. The combination, with a suitable base a box-like holder hinged thereto and an 70 abutment whereon the pins strike when the said holder is depressed, of a rotatable drum for winding on a pin strip, mechanism for rotating the said drum, and a horizontal guide and support in the lower edge of the 75 pin strip, the same projecting inward from the front portion of the holder, as shown and described.

13. In a pin-holder of the class specified, the combination of an abutment whereon 80 the pins strike and the holder for operative mechanism whereby a pin-strip is advanced intermittently and pins are successively ejected therefrom, the same having a body portion formed of plate metal whose bottom 85 and front end are provided with slots and with inwardly projecting integral parts 20 and 24 adapted to serve as lever-stop and strip-guide respectively.

14. The combination, with a base support, 90 of a holder hinged thereto and adapted for containing mechanism for advancing a pin-strip, a sliding pin-abutment arranged in the front portion of the holder, a plate arranged beneath the holder and to whose front end 95 the abutment is connected, said plate being pivotally attached to the rear end of the holder proper and the latter having guides for said abutment, as shown and described
